OTTO R. PEARSON AND CARL V. ANDERSON, OF HIBBING, MINNESOTA.

RAILROAD CROSSING.

Application filed September 8, 1928. Serial No. 304,648.

This invention relates to a highway crossing for railroad tracks, wherein the crossing embodies movable sections to facilitate the repair of the railroad track.

Another important object resides in the hinged transverse bars in spaced relation with each other between the railroad tracks, said bars resting on the ordinary wooden railroad tie and having their ends in abutting relation with respect to the tread, web and base of the track rails and these bars serving as a support for metal plates, secured thereto by suitable fastening means.

The approaches to the railroad crossing on each side are made of several bars similar in construction and in the same spaced relation as the bars between the rails, yet much shorter and held in position against the outside of the railroad track by spikes or other suitable fastening means, said shorter bars also carrying metal plates secured thereto.

A still further object is the provision of a strong and simple highway crossing of few parts capable of being installed permanently and this in comparatively shorter time with respect to other devices of like character.

Other objects and advantages will become apparent during the course of the following description and wherein said novel features are pointed out to produce a highly efficient and removable railroad crossing.

Referring to the drawings wherein like figures indicate corresponding parts;

Figure 1 is a plan view of a railroad crossing showing the preferred embodiment of my invention,

Figure 2 is a transverse section through the track showing my structure in end elevation, and

Figure 3 is a fragmentary side elevation of the crossing structure at the outside of the trackway.

In the drawings, numeral 5 indicates the track rails having the conventional treads 6, webs 7 and bases 8. Our invention resides in a plurality of spaced transverse bars 9, said bars 9 consisting of sections 10—10 and having their inner ends pivoted as at 11.

Resting upon the top of sections 10—10 are plates 12—12, secured thereto by suitable fastening means 13 such as screws, bolts and the like and adapted to be held in a rigid position longitudinally with respect to said rails 5—5.

The outer ends of the sections 10—10 are formed for interfitting engagement with the

treads, bases and webs of the track rails 5—5 and serve to restrain the track from moving inwardly.

Near the outer ends of said sections 10—10 is a depression 14, at which the abutting plates 10—10 define their outer longitudinal edges and render the wheel flanges of passing trains clear of any obstruction within the tread portion of the track.

Obviously, dirt or other matter may be removed from the plates 12—12 through the openings 14' between the outer longitudinal edges of the plates 12—12 and track rails 5—5.

In abutting relation with respect to the outside of the track rails 5—5 and in similar spaced relation as the bars 9 are shorter transverse supporting bars 15—15, in interfitting relation with respect to the outside of said track rails as at 16', and secured to the conventional railroad ties 17 by spikes or other suitable fastening means 18.

Approach plates 16'—16' are arranged on the tops of said bars 15—15 and secured thereto by suitable fastening means 17', said approach plates having their inner longitudinal edges in abutting relation with respect to the outside of the track rails 5—5.

It will thus be seen that we have provided a plurality of transverse supporting bars within the rails, each bar comprising hinged sections 10—10 and supporting a longitudinal plate, said hinged sections adapted to be raised in the direction of the arrow as is clearly illustrated in Figure 2. It will therefore be seen that we have provided a durable and efficient platform for traffic and novel features in the construction of our device wherein railroad crossings may be removed or laid with speed and economy due to the few parts and simple construction.

We desire it to be understood that we may make changes in the construction and arrangement of several parts, provided that such changes fall within the scope of the appended claims.

Having thus described our invention, what we claim as new is:

1. A device of the character described comprising transverse hinged supporting bars between the track rails, transverse supporting bars on the outside of said track rails, the last mentioned bars secured to the cross ties, longitudinal plates secured to said supporting bars within and without the track rails and means for retaining the track rails

in a rigid position with respect to the supporting bars.

2. A railroad crossing comprising a plurality of supporting transverse bars in spaced relation within and without the track rails, said transverse bars within the track rails comprising hinged sections, a plate secured to opposite sections, approach plates adapted to be carried by and secured to said supporting bars within the track, the last mentioned supporting bars being secured rigidly to the railroad ties and said inner and outer transverse supporting bars disposed in abutting relation with respect to the track rails.

15 3. A railroad crossing comprising trans-

verse supporting bars within and without the track rails, said inner supporting bars comprising hinged sections, plates secured to and adapted to rest longitudinally on said inner and outer supporting bars, said plates within the track rails disposed in abutting relation and having their outer longitudinal sides defined by a depression near the outer end of said section, and said outer supporting bars secured to the railroad tie to restrain the track rail from moving outwardly.

In testimony whereof we affix our signatures.

OTTO R. PEARSON.
CARL V. ANDERSON.
